his Attorney.

UNITED STATES PATENT OFFICE.

HENRY J. HAMANN, OF CHICAGO, ILLINOIS.

MOVING PICTURE FILM-WINDING APPARATUS.

1,061,089.

Specification of Letters Patent.

Patented Dec. 9, 1913.

Application filed August 26, 1912. Serial No. 777,876.

To all whom it may concern:

Be it known that I, HENRY J. HAMANN, a citizen of the United States, and a resident of the city of Chicago, county of Cook, and 5 State of Illinois, have invented certain new and useful Improvements in Film-Winding Apparatus, of which the following is a specification.

My invention relates to improvements in 10 film winding apparatus especially adapted for use in moving picture machines and has for its object the provision of an apparatus of this character which is of simple construction and efficient in use.

15 The invention consists in the combinations and arrangements of parts hereinafter described and claimed.

The invention will be best understood by reference to the accompanying drawings 20 forming a part of this specification, and in which,

Figure 1 is a view showing a winding reel in elevation and an unwinding reel in cross section embodying my invention, and 25 Fig. 2 is a section taken on line $\alpha-\alpha$ of Fig. 1.

The preferred form of construction as illustrated in the drawings comprises a disk 1 having an annular recess 2 therein. A 30 broken inwardly compressible spring ring 3 is adapted to enter recess 2 when slightly compressed and expand to frictionally engage the outer wall of said recess to hold said spring ring in position therein. The 35 ends of ring 3 are beveled as at 4 shown in Fig. 1 and spring 3 is provided with inwardly projecting finger pieces 5 secured to the inner wall thereof adapted to facilitate inward compression of said ring and removal from said recess. Disk 1 is secured to the end of a stud shaft 6 concentrically with recess 2 and ring 3, and shaft 6 carries a 40 groove pulley 7 adapted to be driven from the belt 8 from any desired or suitable source of power. Ring 3 is also provided with a peripheral projection 9 adapted to engage in a perforation in the end of a moving picture film 10 or similar flexible strip. Film 10 is normally supported by means of 45 an unwinding reel 11 which is rotatably mounted in a suitable casing as indicated in Fig. 1. Reel 11 is provided with an operating shaft 13 extending from the bottom of casing 12 and provided with a groove pulley 55 14 adapted to engage a twisted belt 15 which in turn runs over a groove pulley 16 on a

shaft 17 arranged under casing 12 as shown. Shaft 17 is operated by means of a belt 18 engaging a groove pulley 19 mounted on shaft 6 as shown. Winding reel 11 is provided with an inner annular flange 20 and an outer flange 21 which have an annular space 22 between them adapted to receive and contain the film during its unwinding. Casing 12 is provided with two guide rollers 23 adapted to facilitate the withdrawal of film 10 from said casing and also is provided with a hinged lid 24 which facilitates insertion of films therein.

In use if it is desired to exhibit the film 70 by passing it before suitable exhibiting mechanism, not shown, the wound film is placed in the annular space 22 in reel 11 and the inner end of the film is passed through rollers 23 and are secured to projection 9 by 75 passing a perforation provided in the end of the film over said projection, as will be readily understood. Then disk 1 is rotated to cause film 10 to wind on to ring 3 spirally, said ring 3 acting as a drum for the purpose. 80 After the film has been completely wound on to ring 3, said ring is removed from disk 1 by engaging finger pieces 5 with a thumb and finger and compressing ring 3 whereupon it may be readily removed from the recess 2. Then the inner end of the film is detached from projection 9 and the film removed in its wound condition, when it may, be placed aside for future use—or may be 85 immediately reexhibited without unwinding, 90 the same from the winding reel 1—3.

The specific form of construction as illustrated constitutes a simple and efficient one.

While I have illustrated and described the preferred form of construction for carrying 95 my invention into effect this is capable of variation and modification without departing from the spirit of the invention. I, therefore, do not wish to be limited to the exact details of construction set forth, but 100 desire to avail myself of such variations and modifications as come within the scope of the appended claims.

Having described my invention what I claim as new and desire to secure by Letters 105 Patent, is:

1. A winding reel comprising a disk having an annular recess therein and an inwardly compressible outwardly expanding broken spring ring inserted in said recess 110 and frictionally engaging the outer wall of said recess, substantially as described.

2. A winding reel comprising a disk having an annular recess therein and an inwardly compressible outwardly expanding broken spring ring inserted in said recess and frictionally engaging the outer wall of said recess; and finger pieces on the interior of said ring adapted to facilitate inward compression thereof, substantially as described.
- 10 3. A winding reel comprising a disk having an annular recess therein and an inwardly compressible outwardly expanding broken spring ring inserted in said recess and frictionally engaging the outer wall of

said recess; finger pieces on the interior of 15 said ring adapted to facilitate inward compression thereof; and a projection on the periphery of said ring adapted to engage a perforation in the end of a strip, substantially as described. 20

In testimony whereof I have signed my name to this specification in the presence of two subscribing witnesses.

HENRY J. HAMANN.
